US0D1081262S

(12) **United States Design Patent** (10) Patent No.: **US D1,081,262 S**
(45) Date of Patent: ** Jul. 1, 2025

(54) **BOTTLE**

(71) Applicant: **Yuelian Hu**, Jinhua (CN)

(72) Inventor: **Yuelian Hu**, Jinhua (CN)

(**) Term: **15 Years**

(21) Appl. No.: **29/923,074**

(22) Filed: **Dec. 27, 2023**

(30) **Foreign Application Priority Data**

Nov. 10, 2023 (CN) 202330733695.4

(51) **LOC (15) Cl.** **07-01**

(52) **U.S. Cl.**

USPC **D7/510**

(58) **Field of Classification Search**

USPC D3/202; D7/509, 510, 511, 523, 529, D7/532, 536, 601, 602, 603, 604, 605, D7/606, 607, 619.1, 622, 629, 709; D9/500, 516, 523, 527, 528, 531, 532, D9/554, 575; D23/211.1

(57)

CLAIM

The ornamental design for a bottle, as shown and described.

DESCRIPTION

FIG. 1 is a perspective view of my new design, showing a bottle;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The line shading in FIGS. 1-8 represents contour and not surface ornamentation.

1 Claim, 8 Drawing Sheets
